UNITED STATES PATENT OFFICE.

GRIFFITH E. BARNETT, OF SALT LAKE CITY, UTAH.

SOAP SHREDDER.

Application filed June 25, 1924. Serial No. 732,819.

To all whom t may concern:

Be it known that GRIFFITH E. BARNETT, a citizen of the United States of America, residing at Salt Lake City, in the county of Salt Lake and State of Utah, has invented new and useful Improvements in Soap Shredders, of which the following is a specification.

It is a purpose of the present invention to provide, in a soap shredder, a construction including a casing for a conical soap shredding body, there being a hopper for receiving the bar of soap so that, as the bar is fed through the hopper, it may contact with the shredding surface of the cone and hence shred the soap into particles.

Shredders of this character have heretofore been produced and, therefore, there is no claim made for the broad idea. However, in the device as heretofore used, the soap particles clog between the shredding cone and the casing, thereby preventing the cone from being freely rotated, especially where it is being operated by manual power.

The present invention aims, as another purpose, to prevent binding between the wall of the casing and the revoluble shredding cone, not only preventing binding at this point but also preventing the soap from clogging around a short shaft with which the shredding cone rotates. It is true that soap in a sense is of a lubricating character but where it is being constantly fed into a shredder wherein there is a space between the cone and the wall of the casing, the soap is very apt to pack between these parts and somewhat retard the action of the shredding cone.

Still another purpose is to provide means consisting of interengaging shoulders to relieve this binding, in conjunction with means for retaining the shoulders in engagement and yet permit the shredding cone to freely rotate.

It is to be understood that the particulars herein given are in no way limitative and that, while still keeping within the scope of the invention, any desired modifications of detail and desired proportions may be made in the apparatus according to the circumstances.

The invention comprises further features and combinations of parts to be hereinafter

set forth, shown in the drawings and claimed. 55

In the drawings:

Figure 1 is a view in perspective of the improved soap shredding machine constructed in accordance with the invention.

Figure 2 is a vertical sectional view. 60

Figure 3 is a cross sectional view on line 3—3 of Figure 1.

Figure 4 is a detail view of the short shaft which rotates with the shredding cone.

Referring to the drawings, 1 designates a bracket which has a bearing 2 for a short shaft 3 which also has a bearing in the smaller end of a conical casing 4. This casing is also secured at 5 to the bracket which at its lower end has an abutment 6. An opposing abutment 7 is carried by the terminal of the bracket and between which abutments 6 and 7 the top of a table 8 may be interposed, there being a clamping screw 9 including a swiveled foot 10 for holding the abutment 75 against the top of the table. 70

Mounted in the casing 4 is a shredding cone 11 provided with struck-up triangular soap shredding points 12. These points extend outwardly of the shredding cone and thereby cause a plurality of openings 13 to be formed in the wall of the shredding cone and through which the shredded soap may pass. Rising from the casing 4 is a hopper 14 through which a bar of soap may pass so as to contact with the shredding points 12. 80

The shredding points 12 extend along the wall of the shredding cone a distance equal to the width of the hopper, whereas the remaining portions of the shredding cone contact with the inner surface of the wall of the casing, and to prevent particles of soap from binding or jamming between the walls of the shredding cone and the casing and reaching the short shaft with which the cone rotates, the cone is provided with a shoulder 15 to contact with a shoulder 16 on the inner surface of the casing 4. The interengaging shoulders are V-shaped, as shown, to prevent the soap from feeding or working back toward the short shaft and behind the rotating cone. 90

In order to relieve the strain on the short shaft in case a small quantity of soap does feed between the surfaces of the cone and the casing and to retain the shoulders in en- 100 105

gagement, a ring 17 is threaded to the larger end of the casing. This ring overlies the margin of the larger end of the shredding cone and acts to keep the shoulders in engagement.

The short shaft has a head 18 which is countersunk in the end wall of the shredding cone, there being a rectangular enlargement 19 adjacent the head to fit a corresponding opening in the end wall of the cone to cause the cone to rotate with the short shaft, the outer end of which has a flat portion 20. A crank handle 21 comprising the crank arm 22 and the handle 15 23 is provided. The crank arm has an opening 24 provided with a flat portion to engage the outer end of the shaft, whereby the shaft and the handle may rotate as one, there being a cotter pin 25 to retain the 20 crank arm in engagement with the shaft. The shaft is held in its bearings in the up-standing bracket and the smaller end of the casing by means of a collar 26 which is secured on the shaft in any suitable manner, as shown.

It will be noted that the opposite end portions of the shredding cone are smooth and extend a distance radially beyond the terminals of the shredding points, thereby preventing the points from engaging with the inner surface of the casing at points beyond the opposite sides of the hopper.

In operation, a bar of soap is fed through the hopper 14 until it contacts with 35 the shredding surface of the cone, then the handle is rotated. Pressure is applied to the bar of soap and as the shredding cone revolves, the soap is shredded into small particles which feed through the openings 40 in the shredding cone, and since the shredder is of conical shape, the particles of soap will feed from the larger end of the cone.

The invention having been set forth, what is claimed is:

45 1. A soap shredder including a casing of conical contour and provide with a soap receiving hopper, a support therefor, a shredding cone having smooth surfaces at its ends to engage corresponding surfaces of 50 the casing, said shredding cone having struck-up shredding points between the smooth surfaces and being formed a distance equal to the length of the hopper, the smooth surfaces of the shredding cone 55 extending radially a distance flush with the terminals of the shredding points, thereby preventing the shredding points from contacting with the surface of the casing at points beyond opposite sides of the hopper, and means operatively mounted in the casing and connected to the shredding cone 60 for rotating the latter.

2. A soap shredder comprising a casing

provided with a soap receiving hopper, a shredding cone having shredding points arranged thereon a distance substantially equal to the length of the hopper, said shredding cone being mounted in the casing and having a relatively close fit with the smooth inner surface of the casing, means mounted in bearings of one end of the casing and connected to the shredding cone for rotating the latter, and means to prevent particles of soap from feeding toward the smaller end of the cone and binding in the same.

3. A soap shredder including a casing of conical contour and provided with a soap receiving hopper, a support therefor, a shredding cone having smooth surfaces at its ends to engage corresponding surfaces of the casing, said shredding cone having struck-up shredding points between the smooth surfaces and being formed a distance equal to the length of the hopper, the smooth surfaces of the shredding cone extending radially a distance flush with the terminals of the shredding points, thereby preventing the shredding points from contacting with the surface of the casing at points beyond opposite sides of the hopper, means operatively mounted in the casing and connected to the shredding cone for rotating the latter, and means to prevent particles of soap from feeding toward the smaller end of the cone and binding in the same.

4. A soap shredder including a casing of conical contour and provided with a soap receiving hopper, a support therefor, a shredding cone having smooth surfaces at its ends to engage corresponding surfaces of the casing, said shredding cone having struck-up shredding points between the smooth surfaces and being formed a distance equal to the length of the hopper, the smooth surfaces of the shredding cone extending radially a distance flush with the terminals of the shredding points, thereby preventing the shredding points from contacting with the surface of the casing at points beyond opposite sides of the hopper, a shaft mounted in the smaller end of the casing and in the support and having a rigid connection with the cone with which the latter rotates, a crank handle connected with the shaft for rotating the same and thereby imparting movement to the shredding cone, and means to prevent particles of soap from feeding between the surfaces of the cone and the casing toward the shaft, thereby preventing binding of the engaging parts.

In testimony whereof he affixes his signature.

GRIFFITH E. BARNETT.
